US00D558632S

(12) **United States Design Patent** (10) **Patent No.:** **US D558,632 S**
Wei (45) **Date of Patent:** **** Jan. 1, 2008**

(54) **WATCH DIAL**

(75) Inventor: **Yang Li Wei**, Dongzhu Town (CN)

(73) Assignee: **New Heritage Ltd.**, Hong Kong (HK)

(**) Term: **14 Years**

(21) Appl. No.: **29/279,338**

(22) Filed: **Apr. 27, 2007**

(51) **LOC (8) Cl.** **10-07**

(52) **U.S. Cl.** **D10/126**

(58) **Field of Classification Search** D10/123-126,
D10/7, 30, 31, 32, 33, 34, 38, 39; D5/28;
D3/235; D6/597, 598, 588, 589; 368/276,
368/281, 282, 285, 228, 232, 80

See application file for complete search history.
